UNITED STATES PATENT OFFICE.

HERMAN L. FRANKE, OF CHICAGO, ILLINOIS.

FLY-SCREEN.

969,777.

Specification of Letters Patent. Patented Sept. 13, 1910.

Application filed October 18, 1909. Serial No. 523,281.

To all whom it may concern:

Be it known that I, HERMAN L. FRANKE, a citizen of the United States, residing at Chicago, in the county of Cook and State of Illinois, have invented certain new and useful Improvements in Fly-Screens, of which the following is a specification.

My invention relates to fly screens, and its principle object, briefly stated, comprehends the production of a device of the above character so constructed that flies within the room may make their exit through the screen, but at the same time prevent the entrance of flies or other insects from the outside.

In the drawings which illustrate the preferred form of my invention, and in which like reference numerals indicate corresponding parts throughout the several views—
20 Figure 1 is an elevation of the inside of the screen. Fig. 2 is a vertical sectional view taken on the line 3—3 of Fig. 1. Fig. 3 is a similar view showing the several sections of the screen closed, and Fig. 4 is a transverse sectional view taken on the line 2—2 of Fig. 1.

Referring specifically to the drawings, 1 indicates the frame of the screen which may be of any desired construction and has 30 pivotally mounted to the side bars thereof a number of screen sections 2 which form the screen proper. These screen sections are of counterpart construction and each comprises a frame 3 formed of sheet metal 35 which is clamped over the edges of the screen material. The frames 3 are rectangular in form and are of such length that they extend entirely across the inside of the frame 1 and have their ends work snugly 40 against the inner side of the side bars of said frame 1. Passing longitudinally through the upper edge of each of the frames 3 is a rod 4 which projects a short distance beyond each side of the frame, as 45 at 5, said projecting ends 5 adapted to be pivotally mounted adjacent the outer faces of the side bars of the frame 1 by means of staples 6, or the like.

As will be seen by referring to Figs. 2 50 and 3 the sections 2 are so arranged that each section will overlap the section there-beneath a suitable distance, and are normally held in spaced relation to each other by means of flat springs 7, one being fas-tened to the lower edge of all but the lower-most of the frames 3 of the sections 2 at

about the middle thereof, and extending upwardly and bearing against the upper edge of the frame 3 of the adjacent section. It will thus be seen that the sections are 60 spaced apart thereby forming free open pas-sages 8 through which flies within the room may escape. It being unnecessary to swing the lowermost of the sections 2, said sec-tion is made stationary within the frame 1, 65 its lower edge being fastened to the end bar of said frame near its inner edge, by any suitable means.

To close the sections at night against the entrance of mosquitos or other insects, I 70 provide the frame 1 with a rotatable mem-ber 10 mounted at each of its ends in suit-able brackets 11 on the inner side of the end bars of said frame 1, intermediate their ends. Portions of the members 10 are offset 75 as at 12, said offset portions 12 being nor-mally in line with the lower edge of each of the frames 3 of the sections 2, except the lowermost. The member 10 is also offset near its lower end, as at 13, said offset por-tion 13 being formed at right angles to the offset portions 12, and serving as an operat-ing handle.

To illustrate the use of my improved screen it will be stated that observation has 85 shown that the tendency of a fly alighting on a screen or other object is, in nearly all cases, to crawl upwardly. Therefore, should any flies alight on the inside of the screen sections 2 they will crawl upwardly 90 through the open passage 8 to the outside, but a fly alighting on the outside of the sec-tions will not crawl downwardly through the passage 8 and enter the room. Practi-cal tests have proven this. However, at 95 night it is best to close the sections, because a light burning in the room will attract mos-quitos and various other insects which may, in some cases, find their way through the passag-8. To close the sections all that 100 is necessary to do is to give the member 10 a quarter turn, by means of the handle 13, which will cause the offset portions 12 to engage the lower edges of the frames 3 and swing the sections 2 inwardly against the 105 ten-sion of the springs 7 until the sections fit tightly against one another, thereby form-ing practically a solid screen. (See Fig. 3.) When the member 10 is turned back again the springs 7 will swing the sections 110 2 outwardly to normal position.

While I have shown my invention as ap-

plied to a window screen it will be understood that it may also be used as a door screen and no limitation is implied by reason of the particular structure shown.

5 I claim:

In a fly screen, the combination with a plurality of screen sections each thereof forming a complete frame and pivotally mounted at their upper edges to, and adapted to swing within a main frame in overlapping relation, springs carried by the lower edges of all but the lowermost of the sections and bearing against the upper edges

of the adjacent section thereabove, to maintain the sections in spaced relation, and a 15 rotatable member having offset portions in line with the lower edges of the frame of the sections, whereby when said member is turned it will press the sections together against the tension of the springs.

In testimony whereof I affix my signature, in presence of two witnesses.

HERMAN L. FRANKE.
